UNITED STATES PATENT OFFICE

2,261,281

ORIENTING BUTTON-ATTACHING MACHINE

Frederick H. Peterson, Watertown, Conn., assignor to The Patent Button Company, Waterbury, Conn., a corporation of Connecticut

Application December 12, 1938, Serial No. 245,278

5 Claims. (Cl. 218—6)

My invention relates to new and useful improvements in button-attaching machines, and has for an object to so construct the hopper that holds the button heads and to so form the chute from the hopper to the attaching station that the buttons, on arriving at the attaching station, will be in a predetermined or oriented position. Thus, when attached, the insignia or reading matter on the button will be in the correct upright, readable position.

As is well known to those skilled in the art, most tack buttons have certain insignia, such as a trade-mark, brand, or a fanciful design on the face of the button. If the button is a solid one, the insignia is stamped or cast in the top face of the button head, while if the button is of the shell type, there is provided a cap in which the insignia or design is stamped.

It is desirable that when the buttons are to be attached to the shoulder straps or bibs of overalls or attached to work coats that the design or brand on the face of the button be in a true upright, readable position.

Another object of the present invention, therefore, is to provide an extremely simple orienting mechanism, especially adapted for orienting certain species of buttons, as shown in patents, to wit, Number 2,170,091, granted to me and Rollin R. Clarke on August 22, 1939, for Tack buttons, and Number 2,170,092, granted to me and Rollin R. Clarke on August 22, 1939, for Tack buttons, which mechanism is readily incorporated in a button-attaching machine of the type shown in the patent granted to me on March 14, 1933 and bearing Number 1,901,375, and in the patent to Franklin R. White, Number 1,901,386, of March 14, 1933. Then, after the buttons have once been thrown into the button hopper of the button-attaching machine, they will be rotated and tumbled in the hopper until such time as certain grooves or cut-away portions in the end of the hubs of the buttons register with certain lands and grooves formed in the peripheral inner face of the hopper, at which time they may pass in their properly oriented position into the chute or raceway to the escapement and then past the escapement to the button-receiving jaws directly over the tack and under the plunger (attaching station). The buttons, when arriving at the attaching station, will be oriented, so that on the descent of the plunger to drive the tack into the cloth and up into the button head (to thus attach the button), the button, with its insignia, will be properly positioned and thus appear in its readable position on the goods to which it is attached.

Still another object of the invention is to provide a mechanism for orienting a certain type of tack button wherein the hopper milled in a certain manner, as hereinafter to be fully explained, may be substituted for the hopper ordinarily used in the above referred-to type of button-attaching machine. Also, specially formed chutes will be substituted to thus make the present form of button-attaching machine capable of orienting the buttons as well as attaching them without any other change in the machine.

Still another object of the invention is to provide a button hopper for a button-attaching machine and its chute with certain forms of undercut grooves, so that the buttons will be fed in a rapid manner, after once assuming the right position in the hopper, to the chute and on down into the attaching station, always remaining in their properly oriented position.

Still another object of the invention is to provide a button-attaching machine that will automatically orient the buttons, permitting the buttons only to pass down to the attaching station after they have been properly and automatically oriented in the hopper and chute.

With these and other objects in view, the invention consists in certain new and novel features and combination of parts, as will be hereinafter more fully explained and pointed out in the claims.

Referring now to the drawings showing a preferred embodiment,

Fig. 1 is a side elevation of a button-attaching machine for orienting the buttons, only that much of the machine being shown as thought necessary to illustrate the invention;

Fig. 2 is an enlarged top plan view of the hopper, the dotted lines showing the manner of orienting the buttons before they pass into the raceway or chute to the attaching station;

Fig. 3 is an enlarged fragmentary sectional view on the line 3—3 of Fig. 2;

Fig. 4 is a fragmentary sectional view taken on the line 4—4 of Fig. 2;

Fig. 5 is a fragmentary sectional view on the line 5—5 of Fig. 2;

Fig. 6 is a bottom plan view of one of the buttons;

Fig. 7 is a side elevation of one of the buttons; and

Fig. 8 is a top plan view showing the insignia on the top face of the button.

Referring now to the drawings and for the moment to Fig. 1, there is shown a button-attaching machine of the type set forth in the patent

granted to me on March 14, 1933, and bearing Number 1,901,375, and in the patent to Franklin R. White, Number 1,901,386, of March 14, 1933. Only that much of the button-attaching machine is shown as thought necessary to illustrate the present invention. The hopper, chute, and tucker mechanism for the tacks are not shown, but it will be understood that they will be the same as shown in the above referred-to patents.

The changes necessary in the present construction to make the machine capable of orienting the buttons are, first, a change in the construction of the under edge of the hopper and, second, a change in the raceway and chute that lead the buttons from the hopper to the button-attaching station.

In Fig. 1, there may be seen a button-attaching head, having the base 1 with its curved upright standard 2, on the end of which is the tubular sleeve or bearing 3, in which operates the main plunger 4, which latter is connected by the link 5 to the main oscillating lever 10. This oscillating lever 10, it will be understood, is operated through an arm 11, which, in turn, is connected to a power clutch, the clutch being operated by a foot pedal (neither of which is shown). The oscillating lever 10 is pivotally mounted, as at 12, to the standard 2 of the base 1.

Beneath the plunger 4 is the anvil 14, on which there is mounted a carrier 15 with the tack-holding jaws 16. There is also shown the button-feeding chute 17, which is spiraled or twisted, as at 18, and which extends upwardly to the tangentially extending ear 19 formed on the base plate 20, on which the rotating hopper 21 is mounted.

Directly beneath the lower end of the raceway or chute 17 are the conventional button-holding jaws 22, which jaws support the button head directly over the anvil, so that on the descent of the plunger, the button-holding jaws will first be pushed downwardly directly over the tack-holding jaws, after which the plunger forces the button head down through the jaws holding the upstanding tack, which has been fed to the anvil by the tucker mechanism (not shown). The cloth, of course, will have been inserted between the tack and the button-holding jaws.

All of the parts so far mentioned are conventional and clearly shown in the patents heretofore referred to.

The slot or raceway in the chute 17, however, is different and will be mentioned more in detail as the specification proceeds.

There may also be seen the main cam lever 23, that is operated on every stroke of the lever 10, this lever 23, in turn, also rotating the hopper for the tacks (not shown) and the tucker slide (not shown), which latter feeds the tacks out to the attaching station to be gripped and held by the tack-holding jaws on the anvil.

It will be understood that the feeding of the button heads and the feeding of the tacks are correctly synchronized, so that when there is a button in the button-holding jaws under the plunger, there will be a tack out on the anvil of the attaching station.

The rotatable button-head hopper 21 is mounted on the post 24 and spaced slightly from the bottom plate 20 and is rotated in a step-by-step movement by the ratchet mechanism 25 through the rod 26 and post 24 and lever 10. The ratchet mechanism is arranged so that on every upstroke of the lever 10, the hopper 21 is rotated through about four teeth of the ratchet mechanism.

In this way, the buttons in the hopper 21 are elevated with the side walls of the rotatable hopper and tumbled, so that in time they will be properly positioned to have their hubs pass through grooves in the periphery of the hopper chute and the bodies of the buttons pass under the hopper (see Fig. 2).

The ratchet mechanism and the hopper are similar to those shown in the aforementioned patents, with the exception that the lands and grooves or valleys on the lower face or end of the hopper are arranged to permit a certain type of button, shortly to be mentioned, only to pass into a raceway tangentially to the hopper when in their properly oriented position.

There is an escapement 17' secured to the chute 17, which permits but one button to pass down the chute to the attaching station on each operation of the lever 10, this escapement per se forming no part of the present invention.

Referring now to the gist of the invention, which is the arrangement of the hopper 21 and its associated raceway and chute, particular reference is made to Fig. 2.

The hopper 21 is a cylindrical casting, open top and bottom and having the spider 27 with an elongated hub or bearing 28, which fits over the post 24, the lower end of the hub being slotted, as at 29, to rest on and engage the pin 30, which is secured transversely of the post 24 and spaced slightly from the bottom plate 20, so that the buttons, when the hubs are properly positioned, may pass from under the walls of the said hopper. This post 24 is rotated in a step-by-step movement by the aforementioned ratchet mechanism 25.

On the inner wall of this cylindrical hopper, there are a plurality of upstanding ribs 31, which also help cause the buttons to be carried around and tumble within the hopper as the hopper is rotated in its step-by-step movement. The hopper may be quickly removed from its post if it is desired. The rotatable hopper is spaced slightly from the plate 20, as mentioned, which latter, in reality, forms the bottom of the complete hopper. So far, the hopper is similar to that shown in the button-attaching machine of the patents heretofore referred-to.

The plate 20 is of slightly larger diameter than the hopper 21 and a raceway 32 is provided in the plate and lug tangent to the hopper, as may be seen to the right of Fig. 2, so that the buttons B may, having passed through the grooves, shortly to be mentioned, in the bottom face of the cylindrical hopper, fall into the raceway 32, which is in registry with the chute 17, heretofore mentioned.

The lower end of the cylindrical hopper is enlarged or flanged, as at 21', and on its under face is milled, as may be seen in Fig. 2, so that the buttons B may, when they are in proper position, pass radially through the hopper to the raceway 32.

As shown in dotted lines in Fig. 2 and in full lines in Figs. 3 and 4, the metal is milled to form the grooves or valleys 33 and leaving the lands 34, these lands being spaced completely around the under peripheral surface of the rotatable hopper. The valleys 33 are of such cross dimension as to permit the hubs of the buttons to pass between the lands 34, providing the buttons are in a certain position.

The one side of the land 34 presents a plane upright wall 35, whereas the adjacent wall on

each succeeding land has a projection associated therewith, as at 36, as may be seen in Figs. 2 and 3.

The lands are also beveled slightly at the inner ends thereof, as at 37, so that if a button is in the position as shown by the topmost button in Fig. 2, the hub may pass through the groove 33 between the lands and out into the raceway 32.

Here the button receives its final alignment. It will be remembered that the right-hand wall of the upper raceway, that is, the wall 42 (Fig. 4), is a part of the base plate 20 and is stationary. Also, it will be understood that said upper raceway has an open side opposite wall 42, so, in reality, the edge of the rotating hopper forms the other side wall of the raceway. The distance between the stationary wall and side wall of the hopper is slightly less than the major diameter of the hub but slightly greater than the width measured on the minor axis of the hub, that is, across the flats. Therefore, as the button passes out of its groove in the rotating cup, it is turned in a clockwise direction, due to the friction of the button head on the plate 20 and the button hub on the wall 42 and the movement of the rotating hopper. The hub of the button striking against the wall 42 and the continued rotation of the hopper then bring the flats of the hub to lie parallel with the sides of the raceway, so that the button can pass down the same. There is enough play between the outer corners of each groove 33 and the segment of the hub still in said groove when said hub contacts the wall 42 to permit this turning. The angle at which the hub strikes the wall 42, of course, varies and depends on how far up it is carried by the hopper before it leaves its groove in the hopper.

However, if the button, with its cut-away portion in the end of the hub, is not positioned opposite the undercut portion of the land in the hopper, it cannot enter the groove 33 and pass into the chute 32.

Referring now for the moment to the button B shown in Figs. 6, 7, and 8, it will be noticed that its hub 38 is slightly flattened on its one side, as at 39, and also flattened on its opposite side, as at 40. Further, the flattened side 40 is undercut, as at 41. Thus, when the button with its cut-away portion 41 is in the position as shown by the topmost button in Fig. 2, the cut-away portion 41 of the hub may fit beneath the cut-away portion 36 of the land 34 and the button thus be permitted to properly enter the raceway 32 tangent to the hopper.

In Fig. 4, which is a sectional view on the line 4-4 of Fig. 2, may be seen the raceway 32 provided with the overhanging wall 42, the outer face 43 of which bears against the flat 40 of the hub 38 of the button B, so that as the button passes down this raceway 32, it will still be held in its oriented position and be prevented from turning as it passes down the raceway.

In Fig. 3, I have shown how the cut-away portion 36 in the lands 34 will receive the hub of the button when in its properly oriented position.

As shown in Fig. 8, the flats on the sides of the hub and the notch or undercut portion on the end of the hub of the button are in planes parallel to a line running twenty degrees from a line perpendicular to the horizontal line of the insignia.

It will be remembered that the button starts down the raceway and into the chute to the button-attaching station in an inverted position

but will be turned over, so that the face will be up when it arrives at the button-attaching station, due to the twist 48 in the chute 17 provided for this purpose.

5 The chute 17 is connected at its upper end to the raceway 32 and the chute is formed with the undercut, exactly like the raceway 32, so that the button is prevented from turning while moving along in the chute. Although the hub may have a slight play and the button be free to move down the chute, it cannot possibly rotate in its travel to the button jaws 22, although it is inverted as it passes through the spiral portion 18 of the raceway 11.

10 15 By having the height of the hub 38 on its one side above the level of the cut-away portion 36 in the lands, the buttons cannot possibly get into the grooves 33 until the cut-away portion 41 in the hub is in registry with the cut-away portion 36 in the lands.

20 It is to be remembered that there will be hundreds of buttons placed in the hopper at the one time and these will be revolved (elevated) and tumbled on each stroke of the lever 10. The buttons at the lower edge of the hopper that are in properly oriented position will be carried upwardly and the hubs will pass between the lands and drop into the raceway 32, where they will pass down to the escapement 17' and there be liberated on each stroke of the plunger 10 to the button-receiving jaws 22. Then, on the descent of the plunger, the jaws 22 will be moved downwardly directly over the tack, while a continuation of the downward movement of the plunger will force the tack through the cloth up into the button head and the button will be in its properly oriented position. The remaining buttons will be revolved and tumbled until they pass properly out into the raceway.

30 40 45 50 Thus, it will be seen that only the buttons in their properly oriented position will pass into the chute or runway, after which they will be prevented from rotating until they are fed into the button-holding jaws. Here, also, they will be prevented from turning, and now being in their proper upright position when attached to the cloth, the insignia or reading matter will be in the proper readable position.

55 As heretofore mentioned, by cutting the lands and grooves in the bottom periphery of the hopper, and by forming the cooperating overhanging walls in the chute, a button, as described with its insignia in certain relation to the cut-out portion of the hub, will always be properly oriented before the attaching operation.

The hopper and chutes may be installed with but little change in the present type of button-attaching machine.

60 65 Having thus described my invention, what I claim as new and desire to secure by Letters Patent is:

1. In a machine for orienting and attaching buttons each of which buttons includes a hub having opposed flats on its side and an aligning wall on the end thereof which wall is eccentric to the central axis of the hub; a rotatable hopper, a raceway adjacent the hopper, the outer periphery of the hopper forming the inner wall of the raceway, an attaching station, a button chute—having overhanging side walls—registering with said raceway and leading to the attaching station, the under surface of the hopper having offset radial grooves, each groove having a projection extending therein from one of its side walls, the said

projection in each groove being also eccentric to the central axis of the button when the button is within its groove, said projection cooperating with the aligning wall on the end of the button and the groove only receiving a button when oriented with respect thereto, the rotation of the hopper in conjunction with the friction between the button head and the bottom of the raceway and the button hub and the far wall of the raceway acting on said button and causing a partial rotation of the button in said raceway so that the flats of the button will lie parallel with the side wall of the raceway, the side walls of the chute also cooperating with the flats on the hub of the button to prevent the button from rotating from its oriented position while passing down the chute to the attaching station, and means for holding the button in its oriented position over the attaching station together with means for attaching the oriented button.

2. In a machine for orienting and attaching buttons each button having insignia on its face and a hub provided with flatted side walls together with an aligning wall in the end of the hub, the aligning wall of the hub being eccentric to the central axis of the hub and parallel with the said flatted walls; including a rotatable hopper having offset radial grooves in its lower surface, one wall of each groove being provided with a projection therein and the said projection coacting with the aligning wall on the end of the button hub to permit the button to enter said groove and pass through said groove only when in a properly oriented position with respect to said groove, a raceway open on its side adjacent the hopper for receiving the button from the hopper, the outer periphery of the hopper forming one wall of the raceway, the width of the raceway being slightly greater than the diameter of the hub of the button through its flats but less than through its larger diameter, the rotation of the hopper in conjunction with the friction between the button head and the bottom of the raceway and the button hub and the far wall of the raceway causing the button in passing from the hopper to the raceway to be aligned in its oriented position, and means for retaining the button in its oriented position until attached.

3. In a machine for orienting and attaching buttons each of which buttons has a hub provided with flatted side walls and an aligning wall on the end parallel with said flatted walls and eccentric to the central axis of the hub; including a rotatable hopper having offset radial grooves in its lower peripheral edge slightly wider than the width of the hub of the button through the flats but less than the larger diameter of the hub, one side wall of each of the grooves being provided with a projection extending toward the

center and adapted to contact with the said aligning wall on the hub of the button, the said grooves being adapted to receive buttons when the latter are in only one aligned position with respect to their radial grooves and in a partially oriented position, a concentric raceway on the side adjacent the periphery of the hopper for receiving the button from the hopper, the distance between the periphery of the hopper and the far wall of the raceway being slightly less than the larger diameter of the hub of the button and slightly greater than the diameter of the hub through the flats whereby the rotation of the hopper in conjunction with the friction between the button head and the bottom of the raceway and the button hub and said far wall of the raceway will cause the button in passing from the hopper to the raceway to be aligned in said raceway, and means registering with the raceway for holding the button in said aligned position until it is attached.

4. In a machine for attaching and orienting buttons each of which buttons has a hub provided with an aligning wall on its end, the said wall being eccentric to the axis of the hub, each of said hubs being provided with flats on its side and parallel with the aligning wall; including a rotatable hopper having offset radial grooves, a side wall of each groove being provided with a projection thereon extending within the groove, said grooves, respectively, receiving a button only when the aligning wall of the hub of the button properly registers with the projection in the groove, a raceway having a diameter small enough to prevent the flatted hub from full rotation when therein and thus hold the same in its predetermined alignment as it passes from its groove into said raceway, and a chute—registering with said raceway—having overhanging walls adapted to also contact with the flats on the hub and hold the buttons in the oriented position they assumed when in said raceway until they reach the said attaching station.

5. In a hopper for dispensing buttons each of which buttons has a hub provided with an aligning wall on its end and flats on its side; a rotatable hopper open at its bottom, offset radial grooves in the under periphery of the hopper, each of said grooves being provided with a projection on one of its side walls and the projection being adapted to contact with the aligning wall on the end of the button, and the portion of the wall beneath the projection and the opposite side wall of the groove being adapted to contact with flats on the side of the hub of the said button to thus hold the button in a predetermined position as it passes through the groove.

FREDERICK H. PETERSON.
